United States Patent Office

Des. 214,670
Patented July 15, 1969

214,670

CRUCIFORM ORNAMENT

Helge M. Stottrup, 764 Sutter Ave.,
Palo Alto, Calif. 94303

Filed July 12, 1968, Ser. No. 12,834

Term of patent 14 years

Int. Cl. D11—03

U.S. Cl. D29—23

FIG.1

FIG.4

FIG. 1 is a perspective view of a cruciform ornament showing my new design;

FIG. 2 is a front elevational view to an enlarged scale, the opposite side being substantially a mirror image;

FIG. 3 is a side elevational view thereof; and

FIG. 4 is a top plan view thereof.

I claim:

The ornamental design for a cruciform ornament, as shown and described.
